UNITED STATES PATENT OFFICE.

WILLIAM F. HAYS, OF OSBORNE'S MILLS, WEST VIRGINIA.

LATCH.

1,142,166.

Specification of Letters Patent.

Patented June 8, 1915.

Application filed May 28, 1914. Serial No. 841,645.

To all whom it may concern:

Be it known that I, WILLIAM F. HAYS, a citizen of the United States, residing at Osbornes Mills, in the county of Roane and State of West Virginia, have invented certain new and useful Improvements in Latches, of which the following is a specification.

This invention relates to a gate and the principal object of the invention is to provide an improved type of latch for releasably holding the gate in a closed position, the latch being so constructed that it may engage the notched plate carried by the post no matter in which direction the gate is swinging.

Another object of the invention is to provide the gate with an improved type of latch housing and to also provide an improved means for moving the latch to a released position.

Another object of the invention is to provide an improved type of catch plate carried by the post of the gate, the plate being so constructed that it will be securely held upon the post and all danger of the plate being worked loose by pounding prevented.

This invention is illustrated in the accompanying drawings, wherein—

Figure 1 is a side elevation showing a gate provided with the improved latching means; Fig. 2 is a sectional view taken along the line 2—2 of Fig. 1; Fig. 3 is an end elevation of the plate carried by the post; and Fig. 4 is a perspective view of the upper end of the gate.

The gate is provided with the vertical end bars 10 and 11 which carry the longitudinally extending bars 12, the longitudinally extending bar 13 being of greater width than the remaining ones so that a longitudinally extending groove may be formed in this bar to form a housing in which the latch 15 is pivotally mounted by means of the pivot pin 16. The end post 11 is provided with a slot 17 communicating with the housing 14 so that the latch may extend through the post. A plate 18 which is preferably formed of sheet metal is secured to the post 11 and bar 13 by means of the screws 19 and has one end portion 20 bent about the post 11 as shown in Fig. 2 to securely connect the strip with the gate and entirely inclose the latch housing. This bent end portion 20 is

provided with a slot through which the latch 55 passes.

The latch operating mechanism is clearly shown in Figs. 1 and 4. The lever or trigger 21 is formed from a strip of rod metal which is bent intermediate its length to form an eye 22 by means of which the lever is pivotally connected with the eye 23 of the supporting bracket 24. This supporting bracket is also formed from rod metal and is twisted as shown in Fig. 4 to assume the proper 65 shape. A U-shaped abutment 25 is provided and engages the trigger to limit the upward movement of the free end of the trigger and thus prevent the trigger from swinging upon its pivot beyond a desired point. The rod 26 which is connected with the free end of the latch by means of the eye 27 is connected with the eye 28 of the trigger by means of the link 29.

From an inspection of Fig. 1 it will be 75 readily seen that when the free end of the trigger is moved downwardly the rod 26 will be drawn upwardly and will raise the latch out of engagement with the catch plate carried by the post 30. The gate can then be 80 swung upon its hinges 31 and 32 by means of which it is connected with the post 33 and can be opened either outwardly or inwardly. The catch plate 34 is secured to the post 30 beneath the cut out 35 and has its upper end 85 portion extending partially across the cut out 35 and cut as shown in Fig. 3 so that the latch may be raised as the gate closes and permitted to easily drop into the notch 36. This catch plate is provided with side wings 90 or arms 37 which extend along the sides of the post 30 and serve to greatly strengthen the plate 34 and prevent any danger of the fasteners 38 being worked loose by pounding. After the gate has been opened the person opening the gate will pass through the same and can then release the gate and permit it to swing back to a closed position. The lower hinge 32 is of the two-point-contact type thus causing the free end of the 95 gate to be swung upwardly when the gate is opened in either direction and thus causing the gate to be closed of its own weight. When the gate closes the gate will swing past the post 30 a few times until its momentum is reduced a sufficient amount to permit the latch 15 to drop into the notch 100 36 and hold the gate in a closed position.

This gate will therefore operate very effectively since it can be opened in either direction and will close itself after the person has passed through and be releasably held in a closed position.

What is claimed is:—

1. A gate provided with vertically extending end bars and longitudinally extending bars connecting said end bars, one of said 10 longitudinally extending bars being provided with a cut out forming a housing communicating with a slot formed in one of said vertically extending bars, a strip inclosing said housing and having one end 15 portion bent to extend about the slotted vertical bar and provided with a slot registering with the cutout of said vertical bar, a latch pivotally mounted in said housing and extending through the slots of said 20 strip and vertical bar, a support carried by said gate and provided with an eye, a trigger provided with an eye engaging the eye of said support to pivotally mount said latch, a U-shaped element carried by said 25 gate and limiting the vertical movement of said trigger, a rod pivotally connected with said latch, and a link pivotally connecting said rod with said trigger.
2. A gate provided with vertically extending bars and longitudinally extending bars, one of said longitudinally extending bars being provided with a cut out forming a housing communicating with a cut out 30 formed in one of said vertical bars, a closure plate secured to said vertical bar and longitudinally extending bar to inclose said housing and having one end portion bent about 35 said vertical bar and provided with a slot communicating with the cut out of said 40 vertical bar, a latch pivotally mounted in

said housing and extending through said vertical bar and strip, a U-shaped support formed of rod metal bent intermediate its length to form an eye, a trigger formed of rod metal bent intermediate its length to 45 form an eye passing through the eye of said support, a U-shaped abutment carried by said gate and passing over said trigger, and flexible means connecting said trigger with said latch.

3. In a device of the character described a movably mounted latch, and operating means for said latch comprising a support provided with an eye, a trigger provided with an eye engaged by the eye of said support to pivotally mount the trigger, an abutment engaging the free end of said trigger to limit its pivotal movement in one direction, a rod pivotally connected with said latch, and a link pivotally connected 55 with said rod and trigger.

4. A gate, a latch pivotally connected with said gate, a post provided with a cut out, a catch plate fitting against said post beneath said cut out and provided with side 65 extensions secured to the side pieces of said post, said catch plate having its upper end portion extending partially across said cut out and being provided with inclined edges leading to a notch to receive said latch when 70 said gate is in a closed position, and means for moving said latch to an inoperative position to permit said gate to be opened.

In testimony whereof I affix my signature in presence of two witnesses.

WILLIAM F. HAYS.
